UNITED STATES PATENT OFFICE.

HERMAN ROSENTHAL, OF NEW YORK, N. Y.

DESIGN FOR A COLLAR.

SPECIFICATION forming part of Design No. 26,313, dated November 24, 1896.

Application filed September 17, 1896. Serial No. 606,185. Term of patent 31 years.

To all whom it may concern:

Be it known that I, HERMAN ROSENTHAL, a citizen of the United States, residing at New York city, in the county and State of New York, have invented and produced a new and original Design for Collars, of which the following is a description, reference being had to the accompanying drawings, forming a part thereof, in which—

10 Figure 1 is an elevation of the collar. Fig. 2 is a transverse section taken on the line 2 2 of Fig 1, and Fig. 3 is a transverse section on the line 3 3 of Fig. 1.

15 The design relates to collars, especially collars adapted for ladies' use, being intended when worn with one edge upward to present a collar of the Elizabethan type, with an apron after the manner of regular ruching, and wherein when the opposite edge is worn up-
20 permost the collar will have the characteristics of regular ruching and an apron of full plaited-cape contour.

The design consists in a collar apparently longitudinally separated into two divisions A and B. The division A is formed of plaits 25 in regular order after the style of ordinary ruching. The opposing division B is also plaited, but the plaits are longer than in the division A and are graduated in length from the center in direction of the ends of the 30 collar.

A minor feature of the design consists in a band C, which extends along the meeting surfaces of the two divisions A and B of the collar.

I claim—

35 The design for a collar herein shown and described.

HERMAN ROSENTHAL.
